WELT GUIDES

Alexander Black, Beverly, Mass., assignor to United Shoe Machinery Corporation, Flemington, N.J., a corporation of New Jersey

Application October 12, 1956, Serial No. 615,654

7 Claims. (Cl. 112—46)

The present invention relates to improvements in Goodyear welt shoe inseam sewing machines and more particularly to welt guides for such machines arranged to direct a preformed welt into the sewing point in the manner disclosed in United States Letters Patent No. 2,509,221, granted May 30, 1950, on application of J. P. Fredericksen.

It has always been assumed that an important prerequisite for a welt guide in an inseam sewing machine is in the fitting of the guide accurately to the welt throughout the entire extent of the surface area on the welt without imparting excessive frictional resistance to its feeding movement during the progress of the sewing operation. To secure properly fitting conditions it has been found necessary heretofore, as a welt moves toward the sewing point in a machine, to provide means for shielding the welt against the pressure of a shoe being presented to a machine until the welt reaches the sewing point. Such shielding means generally is U-shaped and has internal dimensions corresponding with the section of the welt to confine all of its portions closely and a mounting block or frame carries the shielding means in a manner for convenient detachment. There are many forms of shielding means capable of attachment to a single mounting block but whenever the dimensions or shape of a welt are changed substantially, different shielding means must be employed. This is particularly true of a guide for a storm type welt having a weather excluding bead.

An object of the present invention is to produce a superior construction and design of welt guide particularly applicable for use with preformed welts, either of the storm or other type, wherein the same welt confining and shielding parts may be employed for a large range of sizes and styles, which previously could have been sewn only by replacing the shielding means for each change of welt. A further purpose is to reduce substantially the usual frictional resistance to feeding movement of a preformed welt through a welt guide in a Goodyear welt shoe inseam sewing machine, wherein the welt contacting surfaces of the guide are smaller than previously employed and are limited to contact with a few areas on a welt, which areas are selected as being most nearly of universal spacing and of standard dimensions for all sizes and styles, eliminating from engagement with the guide those areas whose dimensions and spacings vary widely.

In the attainment of the objects, above referred to, a curved hook needle shoe inseam sewing machine is provided with a welt guide constructed to direct a preformed welt having an inseam sewing flange and an outsole attaching flange projecting away from each other at an obtuse angle, in which guide there are also provided shielding means comprising a plate portion for supporting the exposed or grain side of the outsole attaching flange, adjustable gage means formed within the shielding means with re-entrant angular surfaces surrounding one corner of the welt to confine the free margin of the outsole flange against the supporting plate portion, the

2

shielding means also including a hooked arm portion extending out of engagement with the outsole flange of the welt, while contacting the inseam sewing flange outside the angle only between the outsole and the inseam flanges, thus leaving the remaining areas on the welt free of frictional engagement. By contacting the areas only of the welt outside of the angle formed between the outsole and inseam flanges, a much greater range of dimensions and styles may be accommodated without replacing or adjusting the portions of the guide relatively to each other. Minor adjustments are, with such guide, sufficient to insure proper directing action on the welt with relatively wide changes in dimensions and styles. While such guide is particularly advantageous in sewing preformed welts, the same type of guide also may be employed satisfactorily with ordinary welts of rectangular cross section, such welts, although of rectangular cross-section, always having their inseam sewing flange portions bent into conformity with a shoe during the insertion of the inseam from the plane of the outsole attaching flange portions to form an obtuse angle, rather than being preformed with an angle beforehand. In order to impress upon the welt a steady action and to compensate in part, at least, for the lack of confinement in other respects, the illustrated gage means projects further in the direction of work feed toward the sewing point in the machine than is usual with this type of guide and actually crosses the plane defined by the curvature of the sewing needle.

Other features of the invention, as hereinafter described and claimed, will be apparent from the following detailed description and accompanying drawings, in which—

Fig. 1 is a view in left side elevation of an inseam sewing machine including a welt guide, embodying the features of my invention;

Fig. 2 is a plan view on an enlarged scale of a welt confined within the welt guide shown in Fig. 1;

Fig. 3 is a detail view in front elevation showing a portion of the sewing needle and the guide of Fig. 2 without the welt;

Fig. 4 is a bottom plan view of the guide;

Fig. 5 is a partially sectional view of the guide in left side elevation;

Fig. 6 is a detail perspective view showing a mounting bracket of the guide of the foregoing figures;

Fig. 7 is a view of a storm welt in end elevation, showing a typical form intended to be directed by the guide of the invention;

Fig. 8 is a view in side elevation showing more clearly the frictionally contacted area and the extent of welt area in which the guide leaves a typical storm welt free of frictional engagement; and

Fig. 9 is a view similar to Fig. 8 but showing an ordinary preformed welt without a weather excluding bead, which also may be directed by a guide without replacing any portion thereof, according to my invention.

Up until recent times the major bulk of commercial Goodyear welts has been made of flat leather with substantially rectangular cross sections, a groove only being provided to receive inseam stitches. More recently, however, with the development of plastic materials it has been found possible to manufacture economically a preformed welt, in which an outsole attaching flange and

an insole attaching flange project at an obtuse angle from each other, so that an inseam may more easily be directed and sewn along the proper line on the welt and the welt may be brought into conformity more readily with the parts of a shoe during sewing. For these reasons the development of modern preformed welt has been accelerated, both in leather and in plastic materials.

With the use of modern preformed welt, whether of

plastic or leather, the problem of guiding it accurately in a Goodyear Inseam Sewing Machine with prior welt guides has been made increasingly difficult. Thus, with the guide of the Frederickson patent, above referred to, a particularly desirable construction has been provided, but in order to accommodate all sizes and styles of welt it has been necessary to have available fifty or sixty different welt confining shields. Replacement of welt shields in an inseam sewing machine frequently is troublesome and time consuming on account of the crowded relation to the other operating parts in the machine and of the danger of injury to the operator's hands by accidental contact with sharpened points of the work piercing instruments. With the present illustrated welt guide it has been found possible to provide shielding means which will accommodate a large range of styles and sizes of welt, including preformed storm welts, without replacement of shield parts, so that as few as three different sets of shield parts may be sufficient to accommodate every known commercial form of welt, including those of the preformed type. The novel features of the illustrated guide with its shield are based on the selection of more or less standard dimensional spacings between certain areas of a welt, to which areas frictional guiding contact is restricted. It has been found that small areas of the welt are sufficiently uniform in their dimensional spacings that little or no adjustment is required to accommodate a relatively large range of welt sizes and styles. With a large range of welt sizes and styles it is possible to direct a welt accurately in a single guide because the frictional contact surfaces between the welt and the guide are substantially less than normally experienced, the welt actually moving more freely through the present guide than through prior guides, while maintaining the welt in proper sewing position with a satisfactory degree of accuracy.

A welt guide illustrative of the invention is shown in Fig. 1 and is arranged with shielding means constructed for directing a modern preformed welt in an inseam sewing machine of the type disclosed in United States Letters Patent No. 1,971,575, granted August 28, 1934, upon application of Alfred R. Morrill. The machine is operated from a main sewing shaft 10 and comprises, in addition to the welt guide, indicated at 12, work feeding and stitch forming devices, including a curved hook work feeding needle 14, a work piercing and feeding awl 16, a looper 18, and a thread finger 20. During an inseaming operation, the shoe being operated upon is held against a back rest 22 by a channel guide 24. The welt guide 12 is secured in a split socket 26 (see Fig. 2) integral with an angle block 28 made fast to the forward end of a welt guide carrier 30. Within the socket is a pin 32 integral with a guide mounting block 34, the pin being clamped in the socket by a bolt 36. The carrier 30 yieldingly presses the welt guide 12 forwardly against a shoe and urges the shoe toward the channel guide 24 during part of the sewing cycle. The carrier is locked in its forwardly pressed position against the force exerted by the shoe and the channel guide 24 during the remainder of the cycle.

A modern preformed storm welt, the cross section of which may be taken as typical of present day use, is shown in Fig. 7, and comprises an outsole attaching flange 38, an inseam sewing flange 40, and a storm or weather excluding bead 42. The inseam and outsole attaching flanges of the welt project at an obtuse angle to each other, that is, they form an angle of slightly more than 90° along the flesh or unfinished side disposed within the angle. The storm bead 42 of the welt projects to the opposite side of the outsole attaching flange 38, which is the finished side exposed on a completed shoe. Thus, the flanges and bead are arranged generally in the form of a T-section, of which the inseam sewing flange 40 and the bead 42 constitute the crossbar, and the outsole attaching flange the stem. A storm welt of this cross section differs from that in use prior to the development of plastic welts, in that the earlier welts were ordinarily flat without angularly

projecting flanges. The weather excluding beads formerly employed projected above the otherwise flat grain sides normally exposed in a completed shoe.

The improved guide 12 for a modern preformed welt, 5 in addition to its mounting block 34, includes an outsole flange supporting plate 44, an edge gage 46 having a re-entrant outsole flange confining angle and a hook-shaped welt shielding arm 48, the latter extending outwardly from the mounting block 34 in spaced relation above the supporting plate and having a vertical welt-directing surface generally parallel to a vertical welt-contacting surface on the edge gage. The re-entrant angle of the gage surrounds one corner of the outsole flange and confines it against the supporting plate.

The mounting block 34 for the guide has two channel-shaped guideways, shown in Fig. 6, the upper one of which receives the arm 48 and the lower one of which fits the edges of the plate 44 and the edge gage 46. The guideways of the block 34 hold the parts from displacement while enabling forward and rearward adjustment. To secure these parts together adjustably in desired relative positions, a bolt 50 passes through the mounting block, the arm, the plate and the edge gage. The hooked arm 48 and the mounting block 34 are not relatively 20 adjustable, the bolt 50 being fitted snugly within a circular opening in each. To accommodate various widths, thicknesses and styles of welt, the edge gage 46 and the plate 44 are moved forwardly and rearwardly, the plate 44 being formed with a slot 52 (Fig. 4) and the edge gage 25 having an open-ended slot 54 through which the bolt 50 passes.

The welt guide of the present invention contacts the storm welt 38, 40 and 42 only throughout areas of limited extent, as shown in Fig. 8. The re-entrant angle of 30 the edge gage 46 includes a horizontal lip 56 overlying the margin at the flesh side of the outsole attaching flange 38, which, together with the vertical side of the re-entrant angle, confines the free margin of the outsole flange against the supporting plate 44. To retain the margin 35 of the outsole flange between the lip of the edge gage and the supporting plate, the hook-shaped arm has at its hooked free extremity an internal, generally vertical convex surface fitting a concavity within the crossbar of the welt. The arm thus contacts the crossbar portion only 40 of the welt surface area between the weather bead and the inseam flange, the arm extending elsewhere out of engagement with the outsole and inseam flanges. To adjust the edge gage 46 properly it is shifted until it 45 presses the crossbar portion of the welt against the internal convex surface of the arm 48. Because of the limited area of contact between the welt and the guide parts a substantial portion of welt is left entirely free of frictional engagement by the guide. In this way the welt is directed accurately without excessive frictional drag 50 during its attachment to a shoe. Where a weather excluding bead is employed, the bead passes through a slot formed between the ends of the arm 48 and the supporting plate 44, the slot being adjusted to provide sufficient width without excessively heavy frictional contact with the bead. It is thus possible to employ a guide according 55 to the present invention for directing welts having storm beads or other surface irregularities for purposes of ornamentation or unusual shoe construction without interfering with the movement of the welt through the guide and without replacement of guide parts when changing welts. The welt guide illustrated in the drawings is effective by reason of its universal utility through a large 60 range of sizes and styles of welt primarily of the preformed type, that is, in which the inseam sewing flange 40 projects from the outsole attaching flange through an obtuse angle of slightly more than 90°.

While the guide shown in Figs. 1 to 8 of the drawings has been described more particularly in connection with a storm welt of T-shaped section, it is equally adaptable 65 for use with other common forms of welt now generally

available in the market. One such common form of welt, while lacking the weather excluding bead 42, is of a pre-formed cross section, in which the inseam and outsole attaching flanges extend also at an obtuse angle to each other. Instead of adjusting the forward end of the outsole flange supporting plate 44, so that it leaves a slot between it and the hooked extremity of the arm 48, the end of the plate 44 may be shifted to a position located just out of contact therewith.

Fig. 9 shows a preformed welt without a storm bead within a guide embodying my invention. The welt therein shown is of a common form capable of being directed by the illustrated guide without replacement of parts. It will accordingly be appreciated that the illustrative guide may also be employed to advantage with a large range of welt sizes and styles not having a weather excluding bead.

In certain instances, and in order to provide a more rigid construction, according to certain features of the invention, it has been found advantageous to join together the supporting plate part and the hooked arm part of the guide in a single piece welt shield, especially where a particular style of welt is regularly employed, adjustments not being required for a considerable range of sizes. When sewing storm welts only, with a single piece shield, it is necessary, however, to provide adequate clearance space for the weather, excluding bead 42. Where the plate and arm parts of the guide are combined, the principles of the illustrated guide with its restricted welt contacting surfaces still are applicable to enable the welt to be directed with accuracy and with minimum adjustments whenever the welt dimensions are changed.

Having thus described my invention, what is claimed is:

1. A shoe inseam sewing machine having a curved hook needle and other stitch-forming devices, a guide adapted to direct a welt having angularly disposed marginal portions across the path of the needle, the marginal portions of the welt constituting an outsole attaching flange and an inseam sewing flange projecting away from each other at an obtuse angle, said welt guide being provided with a mounting block and shielding means on the block comprising a supporting plate for contacting one side of the outsole attaching flange of the welt, and adjustable means having a re-entrant angle within the shielding means for contacting one corner of the outsole attaching flange to confine the free margin of the outsole flange against the supporting plate, in combination with a hooked arm means separate from the plate of the guide for extending out of engagement with the outsole flange while adapted to contact that portion only of the welt outside the angle between the flanges, leaving the remaining areas of the welt free of frictional contact.

2. A shoe inseam sewing machine having a curved hook needle, and other stitch-forming and feeding devices, a guide adapted to direct a welt having angularly disposed marginal portions across the path of the needle, the marginal portions of the welt constituting an outsole attaching flange and an inseam sewing flange projecting at an obtuse angle to each other, and a weather excluding bead forming with the flanges a generally T-shaped section, said welt guide having an attaching bracket, a supporting plate on the bracket for contacting one side of the outsole flange on the welt and means within the guide for contacting the opposite side and edge of the outsole flange on the welt to retain the outsole flange against the supporting plate, in combination with an arm on the guide disposed substantially parallel to the plate and for extending out of engagement with a major portion of the outsole and inseam flanges while being adapted to contact that portion only of the welt between the weather bead and the inseam flange while leaving the weather bead free of frictional engagement.

3. A shoe inseam sewing machine having a curved hook needle and other stitch-forming and feeding de-

vices, a guide adapted to direct a welt having angularly disposed marginal portions across the path of the needle, the marginal portions of the welt constituting an outsole attaching flange and an inseam sewing flange projecting at an obtuse angle from each other, and a weather excluding bead forming with the flanges a generally T-shaped section, said welt guide having an attaching bracket, a supporting plate on the bracket for contacting one side of the outsole flange on the welt and an angular edge

10 confining gage means within the guide for contacting the opposite side and edge of the outsole flange on the welt to hold the outsole flange against the supporting plate, in combination with an arm on the guide separate from the plate, disposed substantially parallel to the plate and for extending out of engagement with a major portion of the outsole and inseam flanges while being adapted to contact that portion only of the welt between the weather bead and the inseam flange along the crossbar of the T-section at its side opposite the outsole flange.

20 4. A shoe inseam sewing machine having a curved hook needle and other stitch-forming and feeding devices, a guide adapted to direct a welt having angularly disposed marginal portions across the path of the needle, the marginal portions of the welt constituting an outsole at-

25 taching flange and an inseam sewing flange projecting at an obtuse angle from each other, and a weather excluding bead forming with the flanges a generally T-shaped section, said welt guide having an attaching bracket, a supporting plate on the bracket for contacting one side

30 of the outsole flange on the welt and an angular edge confining gage means within the guide for contacting the opposite side and edge of the outsole flange on the welt to hold the outsole flange against the supporting plate, in combination with an arm on the guide separate from

35 the plate, disposed substantially parallel to the plate and for extending out of engagement with a major portion of the outsole and inseam flanges while being adapted to contact that portion only of the welt between the weather bead and the inseam flange along the crossbar of the T-section at its side opposite the outsole flange, the arm of the guide being hook-shaped and provided with an internal convex crossbar contacting surface against

40 which the edge confining gage presses the welt.

5. A shoe inseam sewing machine having a curved hook needle and other stitch-forming and feeding devices, a guide adapted to direct a welt having angularly disposed marginal portions across the path of the needle, the marginal portions of the welt constituting an outsole at-

45 taching flange and an inseam sewing flange projecting at an obtuse angle from each other, and a weather excluding bead forming with the flanges a generally T-shaped section, said welt guide having an attaching bracket, a supporting plate on the bracket for contacting one side

50 of the outsole flange on the welt and an angular edge confining gage means within the guide for contacting the opposite side and edge of the outsole flange on the welt to hold the outsole flange against the supporting plate, in combination with an arm on the guide separate from the plate, disposed substantially parallel to the plate and for extending out of engagement with a major portion

55 of the outsole and inseam flanges while being adapted to contact that portion only of the welt between the weather bead and the inseam flange along the crossbar of the T-section at its side opposite the outsole flange, the arm of the guide being hook-shaped and provided with an internal convex crossbar contacting surface against

60 which the edge confining gage presses the welt, said edge confining gage projecting in the direction of feed across the plane defined by the curvature of the needle.

65 70 6. A shoe inseam sewing machine having a curved hook needle and other stitch-forming and feeding devices, a guide adapted to direct a storm welt across the path of the needle, the welt being preformed with an outsole attaching flange and an inseam sewing flange projecting

at an obtuse angle from each other, and a weather excluding bead forming with the flanges a generally T-shaped section, said welt guide having an attaching bracket and an angular welt edge confining gage on the bracket, in combination with other welt confining means surrounding the edge gage on the bracket and including a supporting plate part for contacting one side of the outsole flange on the welt and a hooked part separate from the plate part and having a shank disposed substantially parallel to the plate part and adapted to extend out of engagement with a major portion of the outsole and inseam flanges while being adapted to contact that portion only of the welt between the weather bead and inseam flange along the crossbar of the T-shaped section at its side opposite the outsole flange.

7. A shoe inseam sewing machine having a curved hook needle and other stitch-forming and feeding devices, a guide adapted to direct a preformed welt across the path of the needle, the welt being preformed with an outsole attaching flange and an inseam sewing flange projecting at an obtuse angle from each other, said guide having an attaching bracket and an angular welt

edge confining gage on the bracket, in combination with other welt confining means on the bracket comprising a supporting plate part for contacting the outsole flange on the welt and a hooked part separate from the plate, having a shank disposed substantially parallel to the plate part and adapted to extend out of engagement with a major portion of the outsole and inseam flanges while being adapted to contact the welt along the external angle opposite the outsole attaching flange, the edge gage being adapted to hold the inseam flange of the welt in contact with the hook part of the guide.
